UNITED STATES PATENT OFFICE.

CHARLES E. ONGLEY, OF NEW YORK, N. Y., ASSIGNOR TO GEORGE J. SCHOEFFEL, OF SAME PLACE.

ELECTRIC TIME AND SIGNAL RECORDER.

SPECIFICATION forming part of Letters Patent No. 554,083, dated February 4, 1896.

Application filed December 8, 1893. Serial No. 493,148. (No model.)

To all whom it may concern:

Be it known that I, CHARLES E. ONGLEY, a citizen of the United States, residing at New York city, in the county and State of New York, have invented a certain new and useful Improvement in Electric Signal-Recording Devices, of which the following is a specification.

My invention relates to apparatus for the recording of electrical signals, together with the time at which said signals are made.

I have illustrated my invention in the accompanying drawings, in which—

Figure 1 is a front view in elevation with part of the clock-face broken away to show the mechanism more fully. Fig. 2 is a detail view of part of the mechanism. Fig. 3 is a vertical section taken through the center of the shaft C. Fig. 4 is a perspective view showing the printing-belt. Fig. 5 is a sectional view of a dash-pot or retarding device for controlling the circuit-breakers. Fig. 6 is an elevation from the rear with the back plate removed. Fig. 7 is a diagrammatic view showing the circuit connections to the magnet B. Fig. 8 shows the circuit connections to the magnet D, and Fig. 9 illustrates a piece of tape with a number of signals recorded thereon by my apparatus.

30 A is a clock-movement in any of the usual forms, and a is the shaft operating the minute-hand.

a' is a pinion secured to the shaft.

a² is a pulley suitably mounted, and about 35 the pinion a' and the pulley a² is the printing-belt a³, carrying on its surface type designating the time. The inside of the belt is preferably corrugated to mesh with the teeth of the pinion a'. The figures on this printing-belt a³ are so arranged that the figures exposed on the lower periphery of the pulley a² designate the time at which the clock may be.

B is an electromagnet in circuit, suitably mounted. The circuit connections to this 40 magnet are shown in Fig. 7, having therein the commutators k' to k⁴, and the circuit is controlled by said commutators. This is the form I employ preferably to operate the device, but any other form of circuit-breakers 45 may be employed. These commutators are

intended to be located at stations and the number of makes or breaks of the circuit made thereby to indicate a signal designating such a station.

b' is a lever pivoted at b⁸ and provided at 55 one end with an armature b² for the magnet B. The spring b³ is secured to the screw b⁴ and to the lever b' and having its tension to draw the armature b² away from the magnet.

b⁶ and b⁷ are adjustable swivels at the end 60 of the lever b', to which are secured the cords e² and e³.

C is a shaft upon which is mounted the type-wheel c'. This wheel is provided on its periphery with a series of numbers or characters in the form of type, intended to indicate stations from which a signal may be given—that is to say, from one to nine and the character zero. It will be hereinafter described how with the making or breaking of 70 the circuit these characters will register the number of such makes or breaks, and thus indicate the station from which the signal may be sent. On the same shaft C is the ratchet-wheel c² and also the pinion c³, both 75 of which are secured to the shaft C.

c⁴ is a lever pivoted to the lever b' at i. It is provided with the pawl i' and hook c⁶ and arm c⁷ and pin c¹².

c⁵ is a lever pivoted at c¹³ and provided with 80 the pawl i², the pin c¹¹ at one end engaging the lever c⁴ and the hook c¹⁴ at the other end.

c¹⁶ is a spring having its tension between the hook c¹⁴ and the screw c¹⁷.

c⁸ is a lever pivoted at c⁹ and provided at 85 one end with a hook arranged to engage with the hook c⁶.

c¹⁰ is a quadrant provided on its periphery with teeth c²⁰. This quadrant is pivoted at c¹⁸ and has the arm c¹⁹ engaging one end of the 90 lever c⁸.

i⁴ is a stationary dog preferably made in the form of a fork between the ends of which the lever c⁴ operates. Its end is cut at an angle to the lever c⁴, making an inclined plane 95 which is arranged to engage the pin c¹², operating when the lever c⁴ is raised, to hold the pawl i' in engagement with the ratchet-wheel c² and also to check the movement of the lever c⁴ when it is being released.

D is an electromagnet suitably mounted and in circuit. The circuit connections are shown in Fig. 8.

d' is a lever pivoted at d² and having at one end an armature d³ for the magnet D.

d⁴ is a printing-hammer carried by the lever d'.

d⁵ is an arm projecting from the lever d' and provided with the pin d⁶ to engage the arm c⁷ of the lever c¹. The lever d' is also bent to admit of its passage around the pulley f², which will be hereinafter described, and is provided with the pawl d⁷ which is held against the ratchet of the pulley f² by the spring d⁸.

E and E' are dash-pots or retarding devices suitably secured at e¹⁷ and e¹⁸, controlling circuit-breakers in the circuit to the magnet D. They are duplicates and are shown in section 20 in Fig. 5, where the dotted lines indicate the operative position and the dark lines the normal position thereof.

e⁴ is a cylinder closed at one end and having a head e⁵ at the other, which is provided 25 with two channels e⁶.

e⁷ are valve-stems provided at one end with a ball-valve consisting of a head e⁸ having two passages e⁹, ball e¹⁰, and pin e¹¹ to hold the ball in the valve. This valve is made so that 30 the oil will pass through the same freely as the valve ascends and less freely as it descends.

e¹² are heads secured to the valve-stems e⁷ by set-screws e¹³, and e¹⁴ and e¹⁵ are beveled 35 flanges on said heads.

The valves are sustained by the cords e² and e³ secured to the valve-stems and to the adjustable swivels b⁶ and b⁷ at the end of the lever b'. The dash-pot E is supported in a 40 somewhat more elevated position than E', so that the flange e¹⁵ will engage its contact an interval later than the flange e¹⁴ of the dash-pot E'. The valve-chamber e⁴ is preferably about two-thirds filled with oil or other suitable liquid, indicated at e¹⁶.

F is a spool upon which is wound a tape f'. f² is a pulley provided with a ratchet-wheel f³, with which engages the pawl d⁷. The tape passes from the spool F over the printing-hammer d⁴ and over the pulley f².

f⁴ is a split block secured to the frame of the apparatus, which block carries a flat spring, at the end of which is secured a block f⁵ carrying a roller. This roller bears on the 55 tape f', holding it against the pulley f², so that when said pulley is rotated the tape is fed forward.

G' and G² are pulleys on which is wound an ink-ribbon g which passes between those rollers and under the guides g³ and g⁴ and between the tape f' and the type of the printing-belt a³ and the printing-type of the wheel c'. The pulley G' is connected with the shaft of the pulley f² by a belt g⁵ and operates therewith.

H is an insulated base supporting the pens h' and h², which are insulated from one an-

other. The spring h³ is also secured to said base.

h⁶ is a trip-lever pivoted at h⁷ and carrying a contact-bar h⁸. This trip-lever is arranged to pass between the pens h' and h² when the contact-bar h⁸ comes in contact with said pens and makes circuit connection, as herein-after described. h³ is also an insulated base supporting the pens h⁴ and h⁵.

h⁹ is a spring carried by the insulated base h⁸.

h¹⁰ is a trip-lever pivoted at h¹⁰ and having a contact-bar h¹¹. This trip-bar is also arranged to pass between the contact-pens h⁴ and h⁵ when the contact-lever h¹¹ makes circuit connection between said contact-pens.

The circuit connection to the magnet D is described as follows: x and x' are the main wires in circuit with a source of electrical supply X. 85 x' is connected with the electromagnet D and x with one end of the pen h². The pen h² is also in circuit connection with the pen h⁵. The pen h⁴ is in circuit connection with the pen h', and the pen h' is in circuit connection 90 with the magnet D. The circuit connections last described are controlled by the movement of flanges e¹⁴ and e¹⁵ on heads e¹², as will be hereinafter described.

The operation of my device is as follows: 95 I may either employ an open or closed circuit. I have illustrated the operation of the device in the accompanying drawings as the same may be operated with a closed circuit. It is, however, manifest that the apparatus may be 100 adjusted to operate either with an open or closed circuit. The position shown in Fig. 1 is that when the circuit is closed to the magnet B, which is therefore energized, and the armature b² is held against the pressure of 105 the spring b³ and pawls i' and i² are in position to engage the ratchet-wheel c².

I will first describe the operation of what I term the "selecting mechanism"—that is to say, the mechanism by which the type-wheel 110 is operated to correspond with the making or breaking of the circuit. I have illustrated the circuit connections to the magnet B in the drawings, Fig. 7, and I have shown in said circuit four commutators having contact-pins 115 arranged to make or break the circuit at predetermined intervals. In Fig. 9 I have shown the record of the signals as the same is printed upon a tape after the operation of the device with the commutators k' to k⁴. It will be 120 noted that the commutator k⁴ has two contact-points, thus breaking the circuit twice and recording the figure 2 on the tape. The commutator k³ has four contact-points and records the figure 4 on the tape. The commutator k² has four contact-points, three being together and one after a space sufficient to enable the mechanisms to operate, making the figures 3 and 1 or 31. The commutator k' has six points, the first two representing the figure 125 2 on the tape and four representing the figure 4, indicating the number 24. These commu-

tators with this arrangement are simply given for illustration, and it will be manifest that any number of commutators may be in the circuit, and that any numerical arrangement 5 may be had to indicate the operation of any particular commutator. I may also employ a Morse key or any other circuit-breaker.

Suppose now that the commutator k^4 is operated. This will break the circuit to the 10 magnet B twice and in doing so will with each break throw the lever b' into the power of the spring b^3 , thus causing the pawl i' to operate the ratchet-wheel c^2 and type-wheel c' twice, the pawl i^2 holding said ratchet-wheel 15 in position while each step of the ratchet-wheel is taken. By this operation the figure 2 on the periphery of the type-wheel c' is brought into the printing-field—that is, in position on the lower periphery of said type-wheel—indicating the station where the commutator k^4 is located. The same operation is performed with the commutator k^3 , the operation being performed four times instead of twice. With the operation of the commutators k^2 and k' the same operation is had as 20 last described, with the exception that there is a space between the breaks 3 and 1 of commutator k^2 and between the breaks 2 and 4 of commutator k' . It would be well to note 25 also that with the operation last described, whereby the type-wheel is operated, that the quadrant c^{10} is raised with the operation of the pinion c^8 against the weight of said quadrant, which is normally at the beginning of 30 its contact with the pinion c^8 , as shown in Figs. 3 and 6; and it will also be noted that with the raising of the lever c^4 the pin c^{12} engages the inclined plane of the stationary dog i^4 and the pawl i' is thereby held against the 35 ratchet-wheel c^2 .

I will now describe the operation of the printing and restoring mechanisms—that is to say, the devices for printing from the type-wheel and the time-belt a^8 when the stations 40 are indicated by the signals, as heretofore recited, and at the same time restoring the selecting device and type-wheel to their normal position. These printing and restoring devices are controlled by the electromagnet D, 45 and the circuit to said magnet is controlled by the dash-pots E and E' as follows: When the circuit is broken—say by the commutator k^4 , as heretofore described—the lever b' is thrown into the power of the spring b^3 , and 50 the cords e^2 and e^3 , attached to the end of said lever, raise the valve-stems e^7 and the ball-valves b^8 . The oil in the dash-pots passes through said ball-valves as they are raised. The passage being free there is very little 55 resistance to the passage of the ball-valves through the oil, and with the making of the circuit after the first break the sustaining-cords e^2 and e^3 become slack and the ball-valves fall again into the oil and descend 60 through the same at a slow rate of speed for the reason, as heretofore recited, that the ball in the valve prevents a rapid passage of

the oil through the same, but said valve not being entirely tight it permits the oil to pass through slowly; but it will be seen that the 70 breaking of the circuit twice by the commutator k^4 is intended to be in very rapid succession, so much so that before the ball-valve has time to descend through the oil after the first break the circuit is broken a second 75 time and said valve is again lifted to the first position described, but with the final breaking of the circuit it will descend, the cords e^2 and e^3 being slack, as stated, and with such descent the flanges e^{13} and e^{14} will engage the 80 trip-levers h^6 and h^9 and make the circuit to the magnet D—that is to say, the flange e^{14} will first engage the trip-lever h^6 and make the circuit to the magnet D, and an interval later the flange e^{13} will engage the trip-lever 85 h^9 and make the circuit again to the magnet D.

It has already been described that the dash-pot E' is arranged to operate an interval in advance of the dash-pot E. When the circuit is first made, therefore, to the magnet D 90 the operation is as follows: The armature d^3 is drawn to said magnet D, operating the lever d' and driving the printing-hammer d^4 against the tape, ink-ribbon, and type, thus making an impression upon the tape. At the 95 same time the pin d^6 engages the arm c^7 of the lever c^4 , operating to throw the lever c^4 back, carrying with it the lever c^5 and disengaging the pawls i' and i^2 , and causing the hook c^6 to engage with the hook of the lever c^8 and hold said pawls i' and i^2 out of engagement with the ratchet-wheel c^2 . As soon as the printing operation described is completed by a blow from the printing-hammer, the printing-wheel c' and the ratchet-wheel and pinion with which it is connected are released 100 and fall into the power of the quadrant c^{10} , which descends and brings the printing-wheel 105 back to its normal position—that is to say, where there is no type exposed on its periphery. With the operation last described—that is to say, when the lever d' is operated, the pawl d^7 engages the ratchets f^3 of the pulley f^2 , and as the lever d' descends it moves 110 said pulley carrying the tape one step farther, and also moving the ink-ribbon.

In the operation described above the dash-pot E operates to make the circuit to the magnet D after the printing is completed and the type-wheel has returned to its normal position—that is, where no type is exposed on the printing-field. Therefore, when the printing mechanism operates again with the circuit being made thereto by the dash-pot E, a space is made between the type-wheel, printing on 125 the tape, though the time is recorded.

I have last described the operation when the breaking of the circuit is consecutive, as when the commutators k^4 and k^3 are operated. When, however, it is desired to indicate a 130 number greater than 9, as those indicated in Fig. 9, (31 and 24,) it is necessary to arrange the commutators with a space between the consecutive breaks of the circuit, the dura-

tion of which in the operation of the commutators will admit of the operation of the dash-pot E' after the first consecutive breaking of the circuit, but will cause the circuit again to be broken before the dash-pot E will have time to operate. Hence the second signal will be printed immediately following the first, without a space between them, thus indicating a greater number than 9—that is to say, in the operation of the commutator ^{k²} the space between the breaks 3 and 1 is sufficient to admit of the operation of the dash-pot E'; but before the dash-pot E will have time to operate the circuit will be broken by the single pin or contact-point of said commutator, and both the valves will be raised, as heretofore described, and they will then descend, the contact being made by the dash-pot E' first and the printing performed, so that the number 1 will immediately follow the number 3, thus indicating 31, and with the operation of the dash-pot E the circuit will be made to the magnet D again and the space between 31 and 4 will be made and the time 4.15 will be printed. It will also be noted that the printing operation also records the time at which said record is made by reason of the fact that the time-belt ^{a³} brings the type corresponding to the time into the field and an impression will be made indicating the time, as shown in Fig. 9.

All that has been described has been performed when the circuit is made to the magnet D by the operation of the dash-pot E'. The next operation is when the circuit is made to the magnet D by the dash-pot E, which makes the circuit an interval later than the dash-pot E', as heretofore described. The operation of this is simply for the purpose of making a space on the tape. Of course the time is recorded, as those type are always in position; but there will be no impression from the type on the type-wheel, as there will be no such type exposed in the printing-field.

While I have described herein the operation of my device with a type-wheel having numbers arranged in a designated order, I do not intend to limit myself to that arrangement. I may employ any numerical or alphabetical arrangement in any convenient order, and in the drawings have shown a type-wheel having twenty-four faces. I frequently employ such a type-wheel and provide the same with type designating the numbers of each; but I may, of course, operate the same to designate any number, as heretofore related.

What I claim is—

1. In a signal-recording device, the combination of a type-wheel, a signaling-circuit, a magnet in said signaling-circuit for operating said type-wheel, a printing and releasing circuit, a magnet in the latter circuit for printing from and releasing said type-wheel, and means operated from the magnet in the signaling-circuit, for operating the printing and

releasing magnet after the type-wheel has been operated, whereby a record will be printed from the type-wheel after which the type-wheel will be released, substantially as set forth. ⁷⁰

2. In a signal-recording device, the combination with means controlled electrically to operate a type-wheel, of two retarding devices operated with the operation of the signaling device and arranged to control the circuit to an electromagnet operating means to print from said type-wheel and release the same, one of said retarding devices operating when the signal is wholly or partly completed and the other only when the signal is wholly completed, substantially as described. ⁷⁵

3. In a signal-recording device, an electromagnet in circuit and means for controlling said circuit, in combination with a type-wheel, and means to advance the same one step with each impulse of the magnet, and thus present type corresponding to the number of signals in a printing-field, and means to print from the type thus presented, and to return the type-wheel to its normal position, operated by a second electromagnet in circuit, and means to control the circuit to said second magnet, consisting of a retarding device, operated with the operation of the first magnet and after the completion of the signal, substantially as described. ⁸⁵

4. In a signal-recording device, the combination with an electromagnet in circuit, of commutators arranged to make a signal by controlling the circuit to said magnet, a type-wheel, means to advance the same one step with each impulse of the magnet, and thus present type corresponding to the signal in the printing-field, means for printing from the type thus presented, and to return the type-wheel to its normal position, operated by a second electromagnet in circuit, and means to control the circuit to said second electromagnet consisting of two retarding devices operated with the operation of the first magnet, one controlling the circuit when the whole or part of the signal is completed, the other only when the whole signal is completed, substantially as described. ¹⁰⁰ ¹⁰⁵ ¹¹⁰

5. In a signal-recording device, the combination with an electromagnet in circuit, means for controlling said circuit, a type-wheel operated by ratchet-wheel and pawls, a lever carrying said pawls an armature for said magnet, a spring controlling said lever together with detents to control said pawls, and a quadrant and pinion to restore the type-wheel to its normal position, and to release the detent that controls the pawls, a second electromagnet in circuit, a lever carrying an armature for said second magnet and printing-hammer, and engaging a detent to release the type-wheel, and means to control the circuit to said second electromagnet, consisting of two dash-pots, operated with the operation of the first magnet, an ink-ribbon, a tape for receiving the impressions from the type-wheel, and means for ¹²⁰ ¹²⁵ ¹³⁰

feeding said ribbon and tape, controlled by the operation of the second magnet, substantially as described.

6. In a signal-recording device, the combination with commutators arranged to make a signal by controlling the circuit to an electromagnet, operating the type-wheel, of a retarding device operated by the operation of said magnet and arranged to control the circuit to a second electromagnet, operating the printing and releasing mechanisms, an interval after the completion of the signal, substantially as described.

7. In a signal-recording device, the combination with commutators arranged to control the circuit to an electromagnet, operating the type-wheel, of two retarding devices operated

by the operation of said magnet and arranged to control the circuit to a second electromagnet, operating the printing and releasing mechanisms, the commutators being arranged to control the circuit to operate one of said retarding devices to control the circuit to the second magnet when the signal is wholly or partly completed and the other retarding device only when the signal is fully completed, substantially as described.

This specification signed and witnessed this 22d day of November, 1893.

CHARLES E. ONGLEY.
